UNITED STATES PATENT OFFICE.

ROBERT SAFFORD TOWNE, OF NEW YORK, N. Y., AND FREDERICK B. FLINN OF ORANGE, NEW JERSEY, ASSIGNEES, BY MESNE ASSIGNMENTS, TO PNEUMATIC PROCESS FLOTATION COMPANY, OF NEW YORK, N. Y., A CORPORATION OF DELAWARE.

PROCESS OF AND APPARATUS FOR SEPARATING ORE MATERIALS FROM EACH OTHER.

1,378,920.

Specification of Letters Patent.

Patented May 24, 1921.

Application filed September 12, 1914, Serial No. 861,433. Renewed January 5, 1920. Serial No. 349,639.

To all whom it may concern:

Be it known that we, ROBERT S. TOWNE and FREDERICK B. FLINN, citizens of the United States, residing at New York and 5 Orange, in the counties of New York and Essex and States of New York and New Jersey, respectively, have invented certain new and useful Improvements in Processes of and Apparatus for Separating Ore Materials from Each Other, of which the following 10 is a specification, reference being had therein to the accompanying drawing.

This invention relates to a process for treating ores for the purpose of separating 15 the metalliferous particles from the non-metalliferous particles thereof; also to improvements in apparatus for carrying out the process. The process is of the general class in which air, or equivalent gaseous 20 body, is used for causing the metalliferous particles to separate from a fluid pulp mass and rise to the surface; and is more particularly a process in the subclass in which use is made of relatively large bubbles 25 formed by the introduction of air, or its equivalent, into the pulp mass under slight pressure from an external air body.

In carrying out a method of this sort a pulp is formed by commingling the ore in 30 its original condition with water in suitable proportions, and, generally, there is added, at one stage or another, a quantum of oil or equivalent material for purposes now well known. A column of pulp is formed and 35 the air is forced into the bottom part of this column, generally through a porous septum or diaphragm adapted, under proper conditions of depth of column, pressure of air and degree of permeability of the septum, to form the relatively large bubbles referred to. The pulp is delivered as a continuous supply to the column.

We have found that the ores must be considered in several classes in respect to the 45 general features of the process which we have devised. In the case of some ores we have found it more advantageous to deliver the incoming pulp at horizontal planes which are high relatively to the planes of 50 the porous septum, and in such cases the column may be of relatively lesser horizontal dimensions and prolonged vertically as

required. In respect to other ores we have found that the pulp can be more advantageously delivered in such manner that it 55 will be initially projected over a greater horizontal area while it is moving downward; and in such cases we cause it to enter the main pulp column from points at the periphery, ores of the sort referred to being 60 so largely suspended in the water that they can be carried in a sheet to the center or points approximating it.

But experience has brought us in contact 65 with ores of another class which, either because of the greater specific gravity of their particles, or because of the relatively larger sizes of the particles which are introduced in the pulp, have a tendency to quickly separate from the suspending fluid, and therefore 70 are not subjected for a sufficiently long time to the separating action of the air.

Ores of this class we treat in the manner herein set forth. We find that, as concerns 75 these, it is better to deliver the pulp at or near the vertical axis of a relatively widely extended pulp column, permitting the solid content particles to commence their descent on lines approximately close to the vertical axis, and causing them to move outward as 80 they descend, so that they shall be subjected to repeated actions of the air globules as the latter ascend.

In the drawings one of the numerous forms of apparatus is shown which can be 85 employed in the treatment of ores such as are referred to.

Of the drawings,

Figure 1 is a vertical sectional view showing one form of mechanism embodying the 90 invention;

Fig. 2 is a plan view of the mechanism shown in Fig. 1;

Fig. 3 is a fragmentary plan view, partly 95 in section along the line 3—3 of Fig. 1;

Fig. 4 is a fragmentary sectional view taken along the line 4—4 of Fig. 3;

Fig. 5 is a fragmentary sectional view taken along the line 5—5 of Fig. 3; and

Fig. 6 is a fragmentary sectional view 100 taken along the line 6—6 of Fig. 2.

Referring to the drawings,

1 represents the main tank or receptacle, which is preferably, though not necessarily,

cylindrical in form. It may conveniently be constructed of sheet metal, though any other suitable material may be used when preferred. The receptacle 1 is provided with a conical bottom 2 having radially inclined sides. At the lower end of the conical bottom 2 there is a discharge pipe 3 in which there is a valve 4. Connected with the pipe above the valve is a branch discharge pipe 5 which is preferably formed of flexible hose.

10 Mounted in the receptacle, preferably at about the level at which the vertical side walls join the inclined bottom walls, is an air distributing device indicated as a whole 6 by 7. It comprises an upper plate 7 which is inclined downward from the center toward the periphery. The plate is porous and may be formed of some suitable medium such as silica sponge, carborundum, a plurality of perforated metal plates, sheets of canvas, etc. Below the plate 7 is another plate 8 formed of sheet metal or other imperforate material. Preferably the plate 8 is also conical in form, it being inclined upward from the center toward the periphery. Preferably the plates 7 and 8 are provided with large central apertures in which is fitted a vertical tube 9 which will be further referred to below. The space between the 15 two plates 7 and 8 is preferably divided into annular chambers 10, 11 and 12 by means of vertical partition walls 13, 14 and 15. The outer partition wall 13 is spaced away from the main side walls of the receptacle, leaving an annular space 13^a. The entire device 6 can be supported in any desired way. As shown, it is carried by brackets 16, 16 extending upward from the inclined bottom wall 2.

40 Valved air pipes 17, 18 and 19 communicate respectively with the chambers 10, 11 and 12 and serve to supply air under pressure thereto. By means of the valves in the pipes the pressure in the several chambers 45 can be regulated and controlled as desired.

At the upper end of the tube 9, preferably some little distance above the plate 7, there is provided a cap or plate 20 which closes the upper end of the tube. At the periphery of the plate 20 there is an annular lip or flange 21.

22 is a spout for delivering ore pulp to the plate 20. As shown, the spout is connected at one side to the wall of the receptacle 1 and receives its supply through a pipe 23. In order to provide for the ready deflection of the upward flowing bubbles in the receptacle, the spout 22 is provided with oppositely inclined walls 23, 23 below its bottom, these walls serving to engage the bubbles and guide them to the sides of the spout.

In order to insure the delivery of the pulp from the spout 22 to the plate 20, we provide the tube 24 which is mounted vertically

above the tube 9 and is of substantially the same size. The spout 22 communicates with this tube 24 through an opening 25.

Positioned around the outside of the upper part of the main receptacle 1 is an annular bubble receiver 26. This has an inclined bottom 27 and at its lowermost part it is provided with a discharge spout 28.

As the tank 1 may be of large diameter, we find it advisable to provide means for 75 mechanically assisting the discharge of bubbles from the central parts thereof. The mechanism for engaging these central bubbles comprises the rotating blades 29, 29 which are fixed on the hollow hub 30 surrounding the tube 24. As shown, the hub 30 carries rollers 31, 31 which engage the hub 30 to give the revoluble hub an anti-friction bearing on the tube 24. The hub 30 is connected by means of the arms 32, 32, 80 supported on the ball pivot 33 with a vertical shaft 34, which is driven by the motor 35 through the gearing 36.

In using the apparatus embodying our invention, the ore, after being first pulverized 90 (when pulverization is necessary) is formed into a suitable liquid pulp of which oil, when necessary, may be a constituent. This pulp is introduced in a stream into the spout 22, through which it flows into the tube 24 95 and onto the distributing plate 20. From the plate 20 the pulp flows by gravity over the annular flange 21, and then in generally downward and outward directions to the annular discharge space 13^a.

100 Through the pipes 17, 18 and 19 air is introduced into the chambers 10, 11 and 12 beneath the porous plate 7 and from these chambers the air passes through the porous plate and into the pulp in the receptacle in 105 the form of relatively large bubbles which are substantially uniformly distributed. The ore, as it moves downward and outward, as aforesaid, is engaged by the upward moving air bubbles, and the metalliferous particles 110 thereof are caught by the bubbles and carried upward. The ore, as it passes downward and outward, is repeatedly acted upon by the bubbles with the result that when the periphery is reached all of the metalliferous 115 particles have been caught by the bubbles and removed. The gangue or residue passes downward and outward through the annular passageway 13^a, and then along the inclined bottom wall 2 to the discharge pipe 3.

120 The air pressures in the chambers 10, 11 and 12 may be varied relatively to each other in order to regulate and control the flow of air into the receptacle. In practice, it is advisable, in using a machine of this character, 125 to vary the action of the air as the pulp moves radially, one rate of air supply being most efficient near the center where the pulp is rich and its flow is slow, and another rate of air supply being most efficient near the 130

periphery where the pulp is nearly barren and its flow is more rapid.

The level of the liquid in the tank 1 may be regulated and controlled either by means of the valve 4, or by means of the pipe 5. If the pipe 5 is used the level of the liquid in the tank may be regulated by raising or lowering the outer discharge end of the pipe.

The bubbles carrying the metalliferous particles in their films continue to move upward above the top surface of the pulp and the successively emerging bubbles are carried upward by those that follow, with the result that there is formed a bubble column 15 extending to the top of the receptacle wall. At the top of the wall the bubbles move radially outward under the influence of gravity and are discharged into the annular receiver 26. In this receiver many of the 20 bubbles break up, but those which remain, and the liquid resulting from those which have burst, flow by gravity down the inclined bottom of the annular receiver and out through the spout 28.

On account of the size of the tank many 25 of the bubbles at or near the center would break down before reaching the periphery if the expectation were to have all of them reach the periphery by gravity alone. The 30 rotary blades 29, 29 serve to engage the central bubbles and to push them outward near enough to the periphery so that they can reach it by gravity without breaking down.

We do not herein claim broadly the means 35 for causing differences in the air action at different radial portions of the porous plate; and we do not herein claim broadly the means for assisting the removal of the bubbles from the center of the receptacle. These 40 features are presented and claimed broadly in our co-pending application Serial No. 861,432, filed on even date herewith.

We are aware that it has been proposed to provide rotary blades at the top of a fluid 45 receptacle in ore-treating apparatus. But in the earlier instances referred to these were positioned directly in the horizontal planes of the surface of the fluid, the purpose being to skim from said surface all the materials 50 that rose thereto. The scrapers had their lower parts arranged in the horizontal planes of the hydrostatic overflow of the fluid. In the present mechanism the central bubble-guiding rotary devices are so positioned as to 55 have all of their movable parts operate in planes considerably above the fluid surface so that the lower part of the bubble mass is allowed to freely rise and yet can be gradually induced to move outward toward the 60 upper edge of the receptacle wall over which the bubbles flow or roll. The discharge controlling devices at 4 and 5 are adjusted to hold the top or hydrostatic level of the fluid at a plane considerably below that of the 65 upper edge of the receptacle wall. The ro-

tary bubble-moving device does not extend over the whole area of the receptacle but is so arranged as to leave a free annular space of considerable width. This rotary device is introduced when we use a receptacle of long 70 diameter. With such an apparatus the bubbles at the center tend to break down before they can reach the periphery. It is preferable to avoid entirely having them impinged on by outside bodies. But a suitably arranged and properly adjusted device of this sort can, where the area is large, be used at the center to induce a tendency of the bubbles to move gently toward the edge so that they can, under their own gravity, roll or 80 flow over the rim.

What we claim is:

1. In an apparatus for separating the metalliferous from the non-metalliferous ingredients of an ore mass, the combination 85 of a pulp receptacle having a conical bottom with a discharge opening therein, a porous plate mounted in the lower part of the receptacle with its periphery spaced slightly from the walls of the receptacle, means for supplying air under pressure below the said porous plate and forcing it therethrough to form relatively large substantially uniformly distributed air bubbles, throughout the area of the receptacle and means for 90 supplying ore pulp to the receptacle above the said porous plate, the said pulp being acted upon by the said bubbles to remove the metalliferous ingredients therefrom flowing downward and outward over the 95 periphery of the plate and into the space below it.

2. In an apparatus for separating the metalliferous from the non-metalliferous ingredients of an ore mass, the combination 105 of a pulp receptacle, a porous plate in the lower part of the receptacle inclined downward along lines extending from the center to the periphery thereof, means for supplying air under pressure below the said porous plate and forcing it therethrough to form relatively large substantially uniformly distributed air bubbles, means for supplying ore pulp to the receptacle near the center 110 thereof above the said porous plate, the said pulp flowing downward and outward in the directions of inclination of the plate and being acted upon by the said bubbles to remove the metalliferous ingredients therefrom, and means for collecting the resulting barren 115 pulp at the periphery of the plate and discharging it from the receptacle.

3. In an apparatus for separating the metalliferous from the non-metalliferous ingredients of an ore mass, the combination 125 of a pulp receptacle, a porous plate in the lower part of the receptacle inclined downward along lines extending from the center to the periphery thereof, means for supplying air under pressure below the said po- 130

rous plate and forcing it therethrough to form relatively large substantially uniformly distributed air bubbles, means for supplying ore pulp to the receptacle near 5 the center thereof above the said porous plate, the said pulp flowing downward and outward in the directions of inclination of the plate and being acted upon by the said bubbles to remove the metalliferous ingredients therefrom, walls forming a chamber below the said plate for collecting the resulting barren pulp flowing over the periphery of the plate, and means for discharging the barren pulp from the said chamber.

15 4. In an apparatus for separating the metalliferous from the non-metalliferous ingredients of an ore mass, the combination of a pulp receptacle, a porous plate in the lower part of the receptacle inclined downward along lines extending from the center to the periphery thereof, means for supplying air under pressure below the said porous plate and forcing it therethrough to form relatively large substantially uniformly 25 distributed air bubbles, means for supplying ore pulp to the receptacle near the center thereof above the said porous plate, the said pulp flowing downward and outward in the directions of inclination of the plate and being acted upon by the said bubbles to remove the metalliferous ingredients therefrom, a wall below the said plate in the form of an inverted cone for collecting the resulting barren pulp flowing over 30 the periphery of the plate, and means at the apex of the cone for discharging the pulp therefrom.

5. In an apparatus for separating the metalliferous from the non-metalliferous 40 ingredients of an ore mass, the combination of a pulp receptacle, a porous plate in the lower part of the receptacle inclined downward along lines extending radially from the center to the periphery thereof, means for supplying air under pressure below the said porous plate and forcing it therethrough to form relatively large air bubbles, means for causing the action of the air at one annular portion of the plate to differ from the action 45 at another annular portion, means for supplying ore pulp to the receptacle at points near the center thereof and above the said porous bottom, the said pulp flowing downward and outward in the directions of inclination of the plate and being acted upon by the said bubbles to remove the metalliferous ingredients therefrom, and means for collecting and discharging from the receptacle the resulting barren pulp which reaches 50 the lower peripheral parts of the plate.

6. In an apparatus for separating the metalliferous from the non-metalliferous ingredients of an ore mass, the combination of a pulp receptacle, a porous plate in the lower 65 part of the receptacle, means for supplying

air under pressure below the said porous plate and forcing it therethrough to form relatively large substantially uniformly distributed air bubbles, a closed tube extending upward from the porous plate in the center of the receptacle, means for supplying ore pulp to the receptacle at points above the said porous bottom arranged along the periphery of the said tube, and said pulp being acted upon by the said bubbles to remove the metalliferous ingredients therefrom, and means for collecting and discharging from the receptacle the resulting barren pulp.

7. In an apparatus for separating the metalliferous from the non-metalliferous ingredients of an ore mass, the combination of a pulp receptacle, a porous plate in the lower part of the receptacle, means for supplying air under pressure below the said porous plate and forcing it therethrough to form relatively large substantially uniformly distributed air bubbles, a closed tube extending upward from the porous plate in the center of the receptacle and terminating below the top thereof, a second tube above and in axial alignment with the first tube and separated therefrom, means for supplying ore pulp to the second tube to cause it to flow radially outward through the opening between the tubes, the said pulp being acted upon by the said bubbles to remove the metalliferous ingredients therefrom, and means for collecting and discharging from the receptacle the resulting barren pulp.

8. In an apparatus for separating the metalliferous from the non-metalliferous ingredients of an ore mass, the combination of a pulp receptacle, a porous plate in the lower part of the receptacle, means for supplying air under pressure below the said porous plate and forcing it therethrough to form relatively large substantially uniformly distributed air bubbles, a closed tube extending upward from the porous plate in the center of the receptacle and terminating below the top thereof, a second tube above and in axial alignment with the first tube and separated therefrom, a spout extending substantially horizontally from the periphery of the receptacle to an aperture in the second tube for supplying ore pulp to the said second tube, the said pulp flowing radially outward through the opening between the tubes and being acted upon by the said bubbles to remove the metalliferous ingredients therefrom, and means for collecting and discharging from the receptacle the resulting barren pulp.

9. In an apparatus for separating the metalliferous from the non-metalliferous ingredients of an ore mass, the combination of a pulp receptacle, a porous plate in the lower part of the receptacle, means for supplying air under pressure below the said porous

plate and forcing it therethrough to form relatively large substantially uniformly distributed air bubbles, a spout extending substantially horizontally from the periphery

5 of the receptacle to a point near the center for supplying ore pulp to the central part of the receptacle, the said pulp flowing radially outward and being acted upon by the said bubbles to remove the metalliferous ingredients.

10 ents therefrom, sharply inclined walls at the bottom of the spout for deflecting upward moving bubbles to the sides thereof, and means for collecting and discharging from the receptacle the resulting barren pulp.

15 10. In a mechanism for separating the metalliferous from the non-metalliferous constituents of an ore mass, the combination of a pulp receptacle, a porous plate in the lower part of the receptacle, means for sup-

20 plying air under pressure below the said porous plate and forcing it therethrough to form relatively large substantially uniformly distributed air bubbles, means for supplying ore pulp to the receptacle above

25 supplying air pulp to the receptacle above the said porous plate, the said pulp being acted upon by the said bubbles to remove the metalliferous constituents therefrom, means for collecting and discharging the re-

sulting barren pulp from the receptacle, means without and around the periphery of the receptacle for receiving bubbles discharged over the walls thereof, and a movable baffle in the center of the upper part

able device at the center of the upper part of the receptacle for engaging bubbles and moving them outward toward the said receiving means, said receptacle having a horizontal diameter which is long relatively to

40 horizontal diameter which is long relatively to the capacity of the bubbles to pass from the center to the edge, and the said bubble-moving device being arranged to operate in planes above the surface of the pulp and to leave a wide exposed area adjacent the periphery of the receptacle.

11. In a mechanism for separating the
45 metalliferous from the non-metalliferous
constituents of an ore mass, the combina-
tion of a pulp receptacle, a porous plate in
the lower part of the receptacle, means for
supplying air under pressure below the said

50 porous plate and forcing it therethrough to form relatively large substantially uniformly distributed air bubbles, means for supplying ore pulp to the receptacle above the said porous plate, the said pulp being

acted upon by the said bubbles to remove the metalliferous constituents therefrom, means for collecting and discharging the resulting barren pulp from the receptacle, means without and around the periphery

60 of the receptacle for receiving bubbles discharged over the walls thereof, and a rotatable device at the center of the upper part of the receptacle having outward extending

blades for engaging bubbles and moving them outward toward the said receiving means, said receptacle having a horizontal diameter which is long relatively to the capacity of the bubbles to pass from the center to the edge, and the said bubble-moving device being arranged to operate in planes above the surface of the pulp and to leave a wide exposed area adjacent the periphery of the receptacle. 65 70

12. The herein described process for separating the metalliferous from the non-metalliferous particles of an ore mass, which consists in forming a body of liquid pulp of the ore having a relatively wide horizontal cross area forming bubbles of air at the bottom of the body and permitting them to rise therethrough and adhere to and remove the metalliferous particles, introducing fresh pulp into the said pulp body at points considerably above the plane of bubble formation and near the vertical central axis of the receptacle, causing the said pulp to move downward at the center of the body to the bottom and then outward across the vertical paths of the bubbles, permitting the barren pulp to move vertically past the planes of bubble formation, collecting and temporarily retaining it in a region below said planes, and discharging it from said region under optional control.

13. The herein described process for separating the metalliferous from the non-metalliferous particles of an ore mass, which consists in forming a body of liquid pulp of the ore having a relatively wide horizontal cross area, forming bubbles of air at the bottom of the said body of pulp at points remote from the peripheral portion of the pulp and permitting them to rise therethrough and adhere to and remove the metalliferous particles, introducing fresh pulp into the said pulp body at points considerably above the plane of bubble formation and near the center of the mass of said bubbles, causing the said pulp to move both downward and outward in all directions relative to the center of the mass of said bubbles and across the vertical lines of movement of the bubbles, permitting the barren pulp to move vertically past the planes of bubble formation, collecting and temporarily retaining the pulp in a region below said planes, and discharging it from said region under optional control. 95
